ELECTRICALLY HEATED BED AND
CONTROL DEVICE

Lamont B. Koontz, Deer Lodge, Mont.

Application December 16, 1947, Serial No. 791,957

15 Claims. (Cl. 219—19)

1

One of man's most important and time consuming activities is sleep. Nothing has yet been found or discovered to eliminate the need for sleep and, although much study has been given this problem, little has been done to diminish the amount of sleep necessary or to improve its benefits. Among the necessities for sound and beneficial sleep are a lack of interruption to said sleep, a freedom of movement, proper temperature, humidity and ventilation, a freedom of burdens, such as heavy bed coverings, and an environment conducive to rest and repose.

It has been customary for centuries to sleep under a plurality of covers, temperature control being effected by using more or less of said covers. Serious objections to such regulation include the necessity that sleep be interrupted while adjustments are being made. Further, the covers provide other distractions as well as comprising a burden of weight to be borne by the sleeper. Also, restrictions of movement caused by said covers are a detriment to sound sleep. In raising children, the problem of using a proper amount of covering and keeping the covers on the children is a difficult matter at best and usually results in loss of sleep and exposure for both the children and the parents.

It is therefore an object of this invention to improve the quality of sleep so that its benefits may be increased and its time diminished.

It is another object to minimize or eliminate the difficulties associated with bed coverings by eliminating the need for them, and to make the use of sleeping garments merely concessions to modesty. Closely associated with this is the object of permitting ventilation of the entire body, thus increasing the benefits of the sleep.

It is a further object to secure adequate air movement over a sleeping person and adequate control of said movement without permitting harmful drafts.

It is an additional object to provide suitable conditions for a sleeping person by controlling the heat loss from his body by a control of air movement and by controlled radiant heat.

It is also an object to control conditions on the sleeping portion of a bed by automatic control of radiant heat from an extensive source above and spaced from said bed, said source being in substantial registry with said bed.

It is an object to provide a means for keeping a sleeping person comfortable in spite of varying air temperature, air movement and varying temperature of adjacent masses by effectively controlling the supply of heat.

2

It is another object to provide comfortable sleeping conditions within a bed inclosure by compensating for changes in air temperature, air movement, temperature changes of adjacent masses and changes in relative humidity by effectively controlling the supply of heat.

It is another object to provide an inherently safe heating means for a bed structure comprising a heat radiator of substantially the horizontal extent of the bed with which it is used, said radiator being normally operated at moderate and safe temperature.

It is an additional object of this invention to provide a bed having automatically controlled conditions conductive to beneficial sleep wherein the bed structure is acceptable to the aesthetic nature of its users.

It is a further object to provide the benefits of controlled conditions for sleeping in a structure closely resembling the well known four-poster bed having a canopy.

It is also an object of this invention to improve the heat control characteristics of a canopy bed having a curtain by improving the heat reflecting and reradiating properties of said curtain.

It is a further object to provide a curtain for beds of the sort described wherein the surfaces of said curtain are adapted to reflect radiant heat and which has an inner heat insulating portion.

It is an object to provide a heated bed structure adapted for use with children wherein the heating portion is inherently safe due to the low intensity of its heating effect, the relative inaccessibility of current carrying members and the spacing of the heated canopy above the bed.

It is another object to provide a bed heated by radiant means wherein the source of heat may comprise electricity or a heated fluid.

These and other objects will become apparent upon a study of the following specification and the related drawings, wherein:

Figure 1 is a perspective view, with parts broken away, showing a bed incorporating the present invention.

Figure 2 is an enlarged section view on the line 2—2 of Figure 1.

Figure 3 is an elevation view, with parts broken away and parts in section, of the controller shown in Figure 1.

Figure 4 is a schematic view of a modified canopy member and heating apparatus usable with the bed of Figure 1.

Figure 5 is a plan view of the radiator member

of Figure 4 showing an arrangement of interior baffles.

Figure 6 is a view similar to Figure 5 showing a different baffle arrangement.

Figure 7 is a schematic wiring diagram of the apparatus of Figure 1.

Figure 8 is a view similar to Figure 2 but based on a section through the line 8-8 of Figure 5.

Figure 9 is a vertical section of a portion of a modified curtain for the bed of Figure 1.

Figure 10 is similar to Fig. 8 and shows a modified heat exchange surface.

Referring to Figures 1 to 3 of the drawings, bed 10 comprises posts 11 arranged at the corners of the springs and mattress supporting portion 12, the springs, not shown, supporting mattress 13 in the conventional manner. Obviously, mattress 13 may comprise any conventional sleeping platform and may be covered as desired. Further, while springs are conventionally used between the support means and mattress 13, their use or non-use is of no concern to this invention.

Posts 11 are also used to support canopy 15 in spaced relation above portion 12, canopy 15 having substantially the same horizontal dimensions as said supporting portion. Canopy 15 comprises a frame 16, a heat radiating member 17, an insulating member 18 overlying member 17, and bracket means 19 for attaching members 17 and 18 to frame 16, bracket means 19 being screwed to 16 by screws or the like, not shown. Resistance wires 20, of a material such as Nichrome, are imbedded in member 17 and serve to heat said member when energized. While any suitable synthetic resin, structural plastic, composite construction, or the like, may be used for 17, hard rubber is preferred because of its good electrical, mechanical and thermal properties. Likewise, insulation 18 may comprise any of a large variety of materials but cellular hard rubber is preferred. By suitably bonding members 17 and 18 together, the resulting composite slab 21 is strong, and relatively light in weight and needs little, if any, structural reinforcement.

A plurality of holes 22 are provided in slab 21 for ventilation and they are preferably connected by conduit means 23 to a suitable fan or blower 24 for insuring a positive circulation of air through the bed space. Blower 24 is of any conventional open construction permitting air to flow through it whether operating or not, and desirably is quiet in operation and operable at a plurality of speeds, a lower or normal speed being adequate for normal ventilation and a higher speed being used to remove excess heat and to increase the heat loss, through convection, from a body lying on said bed. Plural speed fans and blowers are well known in the art and are of many types, the blower 24, for the purpose of this disclosure, being of the sort in which different speeds are obtained by varying the applied voltage. While the forced circulation of ventilating air is preferred in the present bed structure, excellent results have been obtained by merely providing holes 22 and relying on the inherent tendency of warm air to rise and flow out through said holes.

To further control the ventilation of the present bed structure, and for other reasons which will appear, a suitable curtain or curtains 30 are hung from canopy 15 and extend to within a few inches of the floor, or at least as low as supporting portion 12. This curtain, or curtains, extends entirely around the bed so that it, canopy 15 and mattress 13 substantially enclose the usable space 31 of the bed. Curtain 30 is slid-

ably attached by hooks 32 to a peripheral angle iron member 33 so that the curtain or curtains may readily be pushed aside when desired. Curtain 30, for most conditions, should be relatively impervious to air and should have a smooth, heat reflective inner surface. Because the smoothness of the surface has considerable effect on the heat reflective abilities of the curtain material, a bright metallic finish appears to be most suitable but a smooth surfaced synthetic resin material, or a resin sized material, is also good. A satin quilted curtain has also been used with good results, the insulating value of the quilted construction minimizing the heat transmission through the curtain and tending to cause the inner surface of the curtain to re-radiate absorbed heat. Another feasible curtain construction is illustrated in Fig. 9 and comprises an inner sheet 37, horizontally disposed spacing cords 38 sewed or cemented to sheet 37, and an outer sheet 39. With this construction, cords 38 serve to space sheets 37 and 39 apart to form air spaces between the sheets, and said cords also act to prevent convection currents in said air spaces. While the above curtain constructions are considered best for general use, a rather porous material may be used in the summer or in rather warm rooms, if desired.

Whatever form of curtain is used, it is preferred that a reasonably tight construction be used between the curtain and the canopy to insure that the ventilating air will flow through the major portion of space 31. For this reason, a suitable sealing flap 40 is attached to said curtain 30 and coacts with member 33 to seal this connection. Obviously, this is only one of several constructions that may be used at this point.

Because the total length of curtain 30 is considerably more than the peripheral distance around portion 12, the curtain hangs in a manner resulting in its horizontal section being of an irregular undulating shape, the innermost extremes of the undulations contacting supporting portion 12, and the more remote portions of the curtain being spaced from 12 sufficiently to form air passages through which air may flow into space 31 to replace that leaving through holes 22. Obviously, if a headboard or the like extends from portion 12 to frame 16, curtain 30 need not extend around such a headboard.

A heat emitting control device 42, as shown in Figure 3, is suspended within space 31 and is used to control the energization of heater wires 20 and blower 24. This device comprises an outer shell 43, an annular partition member 44, a heater 45, a spiral bimetal 46 arranged between partition 44 and shell 43, a knob 47 for adjusting one end of bimetal 46, and a switch blade 48 operated between spaced contacts 69 and 91 by the other end of the bimetal. With a device of this sort, heater 45 is constantly and uniformly energized sufficiently to bring shell 43 up to a temperature of about 85-100 degrees F., heater 45 warming air in the center of partition 44, which tends to rise and establish convection currents around the partition 44, heat being lost through shell 43. With a uniform supply of heat, the temperature of the air circulating over bimetal 46 is determined by the heat loss from shell 43 which is a function of the surrounding air temperature, air motion and radiant heat or temperature of adjacent masses. For a fuller description of a control device of this sort, reference is made to my Patent 2,423,781, issued July 8, 1947.

Because of the sensitive nature of control devices such as 42, it is generally preferable to control load currents by relays which are controlled in turn by the control device. Thus, in Fig. 7, relay 51 is used to control the energization of heater 20 and relay 52 controls the energization of blower 24. A transformer 57 having a primary winding 58 and a secondary winding 59 is used as a source of low voltage current for the control circuits, primary winding 58 being connected to line wires 54 and 55 by wires 61 and 62, respectively. Relays 51 and 52, as well as other accessory equipment, are conveniently located in a suitable box 53 (Fig. 1) from which line wires 54—55 extend.

In operation, with line wires 54—55 energized, heater 45 of control device 42 is energized by the circuit: secondary winding 59, wire 64, ballast resistor 65, wire 66, heater 45 and wire 67 back to secondary winding 59. With device 42 losing heat at a higher than normal rate, due to conditions of air temperature, air motion and radiant heat which would make the human occupant of the bed feel cool, switch 48 is moved into engagement with contact 69 by bimetal 46 and relay 51 is energized by the circuit: secondary winding 59, wire 70, winding 72 of relay 51, wire 73, contact 69, switch blade 48, wire 74 and secondary winding 59. With winding 72 energized, heater 20 is energized by the circuit: line wire 54, wire 75, relay switch blade 76, contact 77, wire 78, heater wire 20, wire 79, contact 80, relay switch blade 81, and wire 82 to line wire 55. Blower 24 is also energized to run at a low speed by the circuit: line wire 54, wire 84, wire 85, resistor 86, wire 87, blower 24 and wire 88 back to line wire 55.

With heater wire 20 energized, one or more of the conditions of air temperature, air motion or radiant heat is sufficiently changed to reduce the heat loss from device 42 and cause switch 48 to disengage contact 69, thus breaking the circuit to relay 51 and deenergizing heater 20. Under normal conditions, heater 20 will then be alternately energized and deenergized sufficiently to maintain the heat loss from 42 at the rate found desirable for comfort.

Should, for any reason, the heat loss from 42 decrease due to conditions which would cause the human occupant of the bed to become too warm, switch blade 48 will be moved by bimetal 46 into engagement with contact 91, thus energizing relay 52 by the circuit: secondary winding 59, wire 70, wire 92, winding 93 of relay 52, wire 94, contact 91, switch blade 48, wire 74 and secondary winding 59. Energizing winding 93 of relay 52 pulls switch blade 95 into engagement with contact 96 which, with wire 97, shunts resistor 86 thus imposing full line voltage on blower 24 and causing it to operate at high speed, thereby increasing the rate of air motion through space 31 and offsetting or diminishing the effects of excessive temperature or the like.

While the above description has been in terms of electric heaters, it is readily apparent that heat may be provided by other means, such as circulating fluid. In Figure 4, member 117 comprises a radiator member having fluid passages therein extending between an inlet pipe 130 and outlet pipes 131, and member 118 comprises insulation as in the previous description. Radiator member 117 is preferably constructed of metal and may be generally flat, as suggested by Figures 1 and 2 or may be slightly curved, as suggested in Figure 8. Passages 122 for ventilation are

provided as before and, of course, may be connected by conduit means to a blower if desired. To prevent leakage of liquid from radiator member 117, the passages 122 are formed through suitable conduits 133, as shown in Fig. 8. Further, the lower surface of 117 may be corrugated, if desired, as shown in Fig. 10, to both stiffen the member and to increase its radiating surface. The fluid passages through 117 may be tortuous, due to baffles 135 arranged as shown in Fig. 5, or may be more direct with distribution effected by orifices 136 in baffles 137, as shown in Fig. 6, these examples being illustrative only.

The heat exchange fluid in the modification of Fig. 4 is caused to circulate by the thermo-siphon principle but a circulator 171 may be used if found necessary. Also, other conventional accessory equipment commonly used with circulating fluid heating systems, not shown, may be provided for the present circulating system, if desired. Outlet pipes 131 connect with a return pipe 141 which connects through circulator 171 to one port of a three way valve 142, another passage of the valve connecting with pipe 143 which leads to the inlet of heat exchanger 144. The outlet of heat exchanger 144 connects to pipe 130, thus forming a circulating path including radiator member 117, pipes 131, pipe 141, circulator 171 (if used), valve 142, pipe 143, heat exchanger 144 and pipe 130 back to 117. Heat exchanger 144 is also connected in fluid flow relation with the domestic hot water system of the house, not shown, pipe 145 being connected to the hot water pipe of the system and pipe 146 being connected to the bottom portion of the hot water tank of said system. Obviously, 144 may be directly heated if desired.

While various arrangements are feasible for controlling the temperature of the water circulated through 117, a good system comprises a by-pass 148 extending from the remaining port of the three way valve to pipe 130, thus by-passing heat exchanger 144. Valve 142 is adjustable from the position shown in which all liquid passes through heat exchanger 144 to an opposite position in which no liquid passes through 144 and all flow is through by-pass 148. Valve 142 is operated by a conventional slow acting geared reversible motor 149 having an operating arm 150 connected to the operating arm 151 of valve 147 by a link 152.

Valve 142 is controlled from a device 42 in a manner generally similar to the operation previously described. With line wires 154 and 155 preferably at a low voltage, heater 45 is energized by the circuit: wire 154, wire 160, ballast resistor 65, wire 161, heater 45 and wire 162 back to wire 155. Assuming that conditions are such that 42 is losing heat at a higher than normal rate and switch blade 48 engages contact 69, motor 149 is energized in a manner to drive arm 150 in a clockwise direction by the circuit: wire 155, wire 163, switch blade 48, contact 69, wire 164, motor 149, wire 165 and wire 154. This direction of operation drives valve 142 in a direction to close the by-pass port and to direct all flow through pipe 143. If a lessened rate of heat loss from 42 causes blade 48 to disengage contact 69 while valve 142 is at an intermediate position, that position will be maintained until device 42 calls for further adjustment of said valve. Should the rate of heat loss from 42 decrease sufficiently to cause blade 48 to engage 91, motor 149 will then be energized by the circuit: wire 155, wire 163, blade 48, contact 91, wire 166, motor

149, wire 165 and wire 154. This circuit energizes motor 149 in a manner to drive arm 150 in a counterclockwise direction and thus adjusts valve 142 in a manner to close off the port to pipe 143 and open the port for by-pass 148, thus diminishing the heat supplied to the circulating liquid.

The above described control system for varying the water temperature is only suggestive for it is clear that other known temperature changing systems may equally well be used. Further, while no blower control has been shown in Fig. 4, this may be provided by an extra contact 91' similar to 91 controlling a relay as in Fig. 7, or by other suitable means.

This application is a continuation in part of my copending application Serial No. 478,581, filed March 9, 1943, and now abandoned.

Because a study of the present disclosure will show that many substitutions and equivalents are useable in the practice of the present invention, the scope of this invention is to be determined only by the appended claims.

I claim:

1. A bed of the four poster type including a mattress supporting portion, a canopy supported by the posts of the bed, said canopy being of substantially the same horizontal extent as said mattress supporting portion and in spaced relation to said portion, said canopy including an outer curtain supporting flange and a heat radiating slab substantially coextensive with said canopy, said slab comprising a lower member having heater wires imbedded therein and having an upper heat insulating portion, ventilating holes through said slab, a blower, conduit means connecting said holes to said blower, curtain means supported by said flange and arranged to enclose the space between said supporting portion and said canopy, said curtain hanging at least as low as said supporting portion, said curtain being arranged to provide at least one air passage between said curtain and said supporting portion, sealing means for preventing air flow between said curtain and said canopy, an electric circuit for energizing the wires embedded in said heater slab, another electric circuit for energizing said blower, and electric circuit controlling means for controlling said circuits, said controlling means including apparatus responsive to the air temperature, air motion and radiant heat in the space between said canopy and said supporting portion.

2. A bed having posts, a spring and mattress supporting portion attached to said posts, a canopy member supported by said posts in spaced relation to said supporting portion, said canopy being of substantially the same horizontal extent as said supporting portion, said canopy including a lower heater member and an upper insulating structure, ventilating openings through said canopy, a curtain extending between said canopy and said supporting portion and substantially enclosing the space between said canopy and said supporting portion, energy supply means for said heater member, energy control means for said supply, and condition responsive means located in the space between said canopy and said supporting portion and connected in controlling relation with said energy control means, said condition responsive means including heat emitting thermostatic means.

3. A bed having supporting means for a mattress, a canopy member for said bed, structural means for positioning said canopy member in an

appreciably spaced relation above said supporting means, said canopy member including a heat radiator for radiating heat downwardly toward said supporting portion, a curtain extending between said canopy and said supporting portion and arranged to enclose the space between said canopy and said supporting portion, said curtain having a heat reflective inner surface, ventilating air passages around said supporting means, ventilating air passages communicating with the upper portion of said enclosed space, means for increasing the temperature of said radiator, and controlling means for said radiator including apparatus responsive to the air motion, air temperature and radiant heat within said enclosed space.

4. A bed structure comprising a sleeping platform, a canopy member above and in spaced relation to said platform, ventilating openings in said canopy, the under side of said canopy comprising a heat radiating member, means for raising the temperature of said member, means for regulating said temperature raising means, and apparatus responsive to the air temperature, air motion and radiant heat effects within the space between said platform and said canopy connected in controlling relation to said regulating means.

5. A bed structure comprising a sleeping platform, a canopy member supported above and in spaced relation to said platform, said canopy member comprising a heat radiating slab of substantially the same extent as said canopy, means enclosing the sides of the space bounded by said platform and said canopy member, ventilating openings in said canopy member, means for inducing air flow upwardly through said openings, and means responsive to air temperature, air motion and radiant heat conditions within said enclosed space for controlling the rate of operation of said air flow inducing means.

6. A curtain for a heated bed structure of the sort having a canopy spaced above the sleeping portion, said curtain having an inner side and comprising soft and flexible spaced sheets of material, the innermost sheet of material having a smooth heat reflective inner surface, vertically spaced horizontally extending soft and flexible spacer means arranged between said sheets of material, attachment means arranged along the inner side and upper portion of said curtain to facilitate attachment of the curtain to a canopy, and sealing flap means arranged along the inner side and upper portion of said curtain and extending away from said curtain in a manner to effect a seal between said curtain and a canopy to which the curtain may be attached.

7. A heated bed comprising, in combination, a horizontal portion adapted to be slept thereon, an upper canopy member spaced from said portion and in substantial registry therewith, said canopy member including an under heat radiating surface of substantially the extent of said portion, means for causing said surface to radiate heat, means jointly responsive to air temperature, air motion and the temperature of adjacent masses, said responsive means being located between said portion and said member, means for connecting said responsive means in controlling relation to said causing means, and means for effecting a measure of control of air movement in the space between said portion and said member.

8. A four poster bed having an upper canopy member, the under surface of said member comprising heat radiating means, curtain means sus-

pended from said canopy member and substantially enclosing the space between said canopy member and the bed proper, said curtain contacting said bed proper at spaced points, means supplying said member with energy to cause said under surface to radiate heat, and controller means within the space enclosed by said member, said curtain and the bed proper arranged to control said energy, said controller means within said space being jointly responsive to a plurality of factors including radiant heat which affect heat loss from a heat generating body.

9. In combination, a bed, a substantially horizontal member spaced an appreciable distance above and in substantial registry with said bed, means enclosing the space between said bed and said member, means for supplying heat to said space, condition responsive means within said space jointly responsive to air temperature, air motion and the temperature of adjacent masses, and means connecting said condition responsive means in controlling relation to said supplying means.

10. In combination, a bed, a canopy above said bed, curtain means substantially enclosing the space between said canopy and said bed, means radiating heat within said space, passages through which air may flow through said space, circulating means for varying the rate of flow of air through said space, and condition responsive means within said space jointly responsive to air temperature, air motion and the temperature of adjacent masses, said control means being connected to control said means radiating heat and said circulating means.

11. A canopy member for a bed, said member having substantially the same horizontal dimensions as the bed with which it is intended to be used, said member comprising a lower portion having an underside heat radiating surface and including means for heating said surface, an insulating portion above and attached to said lower portion for minimizing heat flow upwardly from said lower portion, a peripheral frame for said member, said frame constituting supporting means for said lower and insulating portions of said canopy member, and registering passages through said lower portion and said insulating portion for permitting air to flow therethrough.

12. In a bed structure, in combination, a body supporting portion, a heat radiating means spaced above said supporting portion, flexible curtain means for substantially enclosing the space between said supporting portion and said radiating means for restricting horizontal air movement through said space, and means jointly responsive to the conditions of radiant heat, air temperature and air motion within said space for controlling said heat radiating means.

13. In combination with a bed having a body supporting portion, a canopy member spaced above said bed and including a heat radiating surface of substantial extent arranged to radiate toward said supporting portion, means for supplying energy to said member for causing said surface to radiate heat, and control means connected in controlling relation to said supplying means, said control means being arranged to respond to conditions within the space between

said canopy member and said supporting portion and including a heat emitting thermostatic means of the sort affected by a plurality of the same conditions which affect the rate of heat loss from a human body.

14. A heated bed comprising, in combination, a sleeping platform, a canopy in spaced relation above and in substantial registry with said platform, said canopy including an extensive radiant heat means directed toward said platform, means for controlling said radiant heat means, ventilating openings in said canopy, vertically arranged curtain means suspended by its upper portion from said canopy and arranged to enclose the space between said canopy and platform, said curtain means comprising an inner sheet of material having a relatively smooth heat reflecting surface, an outer sheet of material, vertically spaced horizontally extending flexible spacer means arranged between said sheets of material, said curtain means being flexible enough to hang freely and extensive enough to hang in undulating folds, and sealing means arranged between the upper portion of said curtain means and said canopy to minimize air flow between said canopy and the upper portion of said curtain means.

15. In combination with a bed having a body supporting portion, a canopy member spaced above said bed and including an underside heat radiating surface of substantial extent, means for supplying energy to said member to cause said surface to radiate heat, and control means connected in controlling relation to said supplying means, said control means including means jointly responsive to the air temperature between said supporting portion and said canopy and to a condition indicative of the radiant heat from said radiating surface.
